[57] **CLAIM**

The ornamental design for a multiple seating unit, as shown and described.

DESCRIPTION

FIG. 1 is a perspective view of multiple seating unit showing my new design;

FIG. 2 is a top plan view thereof;

FIG. 3 is a front elevation view thereof;

FIG. 4 is a left end elevation view thereof;

FIG. 5 is a right end elevation view thereof; and,

FIG. 6 is a rear elevation view thereof.

The fragmented cross-hatching shown on the seat and backrest members is understood to represent fabric and would be continuous throughout the implied areas. The broken lines shown on the sides of the seat and backrest members are understood to represent stitching.
